UNITED STATES PATENT OFFICE.

GEORGE I. ALDEN, OF WORCESTER, MASSACHUSETTS, ASSIGNOR TO NORTON GRINDING COMPANY, OF WORCESTER, MASSACHUSETTS, A CORPORATION OF MASSACHUSETTS.

METHOD OF GRINDING.

1,081,082.

Specification of Letters Patent.

Patented Dec. 9, 1913.

Application filed February 11, 1910. Serial No. 543,298.

To all whom it may concern:

Be it known that I, GEORGE I. ALDEN, a citizen of the United States, residing at Worcester, in the county of Worcester and State of Massachusetts, have invented a new and useful Method of Grinding, of which the following is a specification.

This invention relates to a method of grinding thin knife blade and cutter blanks. Blanks of this kind have been ground ordinarily by hand on natural stones and any attempts that may have been made heretofore, so far as I am aware, to grind them automatically and particularly on artificial stones, have been commercially unsuccessful. This is due to the fact that these blanks easily become burned when ground in this way, and no effective means was known for avoiding it.

This invention is designed for the purpose of overcoming these difficulties and providing a practical method and efficient means for accomplishing this result.

Reference is to be had to the accompanying drawings in which—

Figure 1 is a front elevation of a preferred form of machine for carrying out this invention. Fig. 2 is a sectional view showing certain details thereof, and Fig. 3 is a plan showing a cutter in position for grinding and illustrating how the stream of water is applied thereto.

Several kinds of blades are manufactured from blanks which have square edges that must be ground off to an acute angle before they are put upon the market. This particularly is the case with mowing machine knives or cutters. So far as I am aware, such articles have ordinarily been ground in the shop practically by hand, that is, each blade is manipulated by a workman on the surface of a natural grinding stone. Obviously, much greater speed and economy in production could be obtained if these blades could be ground on artificial stones, as for example, emery or corundum wheels which have a much more rapid cutting action than the natural stones. Heretofore it has been regarded as commercially impracticable to grind thin blades, such as mowing-machine cutter-sections, upon such artificial wheels, by reason of the liability of burning the blades or drawing their temper, even when the blades were completely flooded by water.

The object of the present invention is to

provide an apparatus and method whereby this difficulty may be overcome, so that an artificial grinding wheel, even of comparatively fine grain, may be used without danger of injury to the blanks. In order to accomplish this result I have discovered that it is not sufficient to cool the blades in any way heretofore known, as flooding the blades with cold water under ordinary conditions will not carry away enough heat, and even the entire submersion of the blades in cold water would not cool them with sufficient rapidity when operated upon at high speeds by artificial grinding wheels of suitable fineness. I have discovered however, that the heat can be carried away by introducing cold water on the blades while being ground under a high pressure and at a correspondingly high velocity and directing that water on the side of the blade opposite the wheel in a fine stream along a line slightly back from the extreme sharp edge being formed, and parallel thereto. I have found in practice that when operating upon ordinary mowing machine cutters, such as are now manufactured in large quantities in this country, if the steam is directed in the manner above described, a pressure of from 100 to 150 pounds per square inch is very suitable for the purpose. I believe that one reason for the decidedly different result obtained by the use of water under pressure in this way is due to the fact that when the water is applied to the blades in a comparatively quiescent state, the heat of the blank is sufficient to partially vaporize the water and cause minute bubbles or particles of vapor to adhere directly to the surface of the blade. The vapor as is well known is not as good a conductor of heat as the water itself, and consequently, it tends to hold the heat. By applying the water under sufficient pressure to cause it to flow with comparatively great rapidity, the vapor has no chance to form or if it does form it has no opportunity to cling to the surface of the blank, but is forced to move along the same. As soon as it is dislodged from its original place of formation, it will move out of close contact with the surface of the blade, so that the water can come into contact with the metal. As no particle of steam can remain for any appreciable length of time in any place, the water has a chance to get at every part of the surface of the blank. In this way, there-

fore, an efficient cooling is secured, and it has been amply demonstrated in practice that the thin blanks can be ground in this way on an emery or corundum wheel of comparative fineness at a very high speed without danger of burning.

The invention is illustrated in a form in which a base 4 supports a tank 5 in which are mounted emery or other artificial grinding wheels 6. The cutter blanks B are held on a table plate 7 in position for grinding by plungers 8. The mechanism for operating the plungers does not constitute a part of this patent but toggle levers 9 are shown. 15 Two wheels are shown so that the blanks can be moved along the table plate from one to the other and ground on both sides.

A pump 10 of any desired character is provided drawing water from any source, 20 preferably from a settling tank 11 and supplying it to a pressure tank 12 under considerable pressure. I have found for example that a pressure of 100 to 150 pounds per square inch is very suitable for this 25 purpose. From this tank the water is forced through a pipe 13 into a pair of distributing pipes 14 through a valve 15. From each of the pipes 14 it passes by means of connections 16 into a chamber 18 in each of 30 the plungers 8. The support for each plunger is provided with an elongated passage 19 for receiving the connection 16 in all positions of the plunger. The bottom of the plunger is provided with a long narrow 35 slot 20 by which the water issues in direct contact with the blank along a line a little back from the edge during the entire time during which the blank is being ground. In fact the cooling water under this heavy 40 pressure is discharged on the blade throughout the time while it is in position so that in addition to cooling the blade it keeps the other parts of the mechanism cool.

I have found in practice that by providing 45 a flow of water under high pressure the heat is carried off with such rapidity that even with thin blanks of the particular temper required for mowing machines no appreciable burning or temper drawing 50 takes place. The water is discharged over the blades on the surface of the stones and issues from an opening 21 in the casing 5. It then passes into the settling tank where it is strained and settled so that the particles 55 removed from the stones are left in the bot-

tom and the clear water is used over and over.

While I have illustrated and described the invention as applied to the grinding of mowing machine knife sections or blanks, 60 I am aware that many modifications can be made therein and that it can be applied to the grinding of other edged implements and tools without departing from the scope of the invention as expressed in the claims. 65 Therefore I do not wish to be limited to the exact form or sequence of steps of the invention described nor to the exact use of the invention referred to but

What I do claim is:—

1. A method of grinding cutter blanks which consists in applying them to a grinding wheel and forcing a cooling liquid under high pressure and velocity against the blank on the side opposite the wheel in a thin 75 stream along a line parallel with and at a short distance from the extreme edge being ground.

2. A method of grinding cutter blanks which consists in applying them to a grinding wheel and forcing a cooling liquid under high velocity against the blank along a line parallel with the extreme edge being ground. 80

3. A method of grinding mowing machine knife-section blanks, which consists 85 in applying first one edge and then the other to a pair of grinding wheels, and while the edges are in contact with the wheels applying a thin stream of water under pressure near said edges. 90

4. A method of grinding blanks, which consists in applying the cutting edge thereof to the surface of a quick cutting grinding wheel, holding the blank in substantially stationary position until ground, and constantly forcing cooling fluid under pressure of more than one hundred pounds per square inch against the blank in a thin stream parallel with, and uniformly throughout the extent of, the cutting edge and at a slight 100 distance therefrom, in position to run over the cutting edge on the wheel.

In testimony whereof I have hereunto set my hand, in the presence of two subscribing witnesses.

GEORGE I. ALDEN.
